J. HEINEKE.

STRAW STACKER.

APPLICATION FILED MAR. 15, 1902.

NO MODEL.

2 SHEETS—SHEET 2.

The image contains two technical drawings of a mechanical device, labeled Fig. III and Fig. IV.

Fig. III (Bottom Left): This drawing shows a side view of a mechanical assembly. It features a vertical cylinder 30 with a piston 29. A rod 23 connects the piston 29 to a lever system. The lever system includes a fulcrum 21, a connecting rod 24, and a lever 20. A small circular component 19 is attached to the lever 20. The assembly is mounted on a base 27, which includes a circular dial 10 with markings from I to XII. A label 31 is located near the base.

Fig. IV (Top Right): This drawing shows a top-down view of a circular component 6. The component has a central hole and a slot 4. A rod 20 is inserted into the slot 4. The rod 20 is connected to a lever system, which includes a lever 16, a connecting rod 20, and a rod 25. The lever 16 is connected to a valve 14. The entire assembly is mounted on a base 2, which includes a circular dial 10 with markings from I to XII. A label 37 is located near the base.

UNITED STATES PATENT OFFICE.

JOHN HEINEKE, OF SPRINGFIELD, ILLINOIS, ASSIGNOR OF TWO-THIRDS TO MARTIN HEINEKE AND CHARLES HEINEKE, OF SPRINGFIELD, ILLINOIS.

STRAW-STACKER.

SPECIFICATION forming part of Letters Patent No. 724,097, dated March 31, 1903.

Application filed March 15, 1902. Serial No. 98,391. (No model.)

To all whom it may concern:

Be it known that I, JOHN HEINEKE, a citizen of the United States, residing at Springfield, in the county of Sangamon and State of Illinois, have invented certain new and useful Improvements in Straw-Stackers, of which the following is a full, clear, and exact description, reference being had to the accompanying drawings, forming part of this specification.

My invention relates to a straw-stacker combining both the pneumatic and apron-carrier features heretofore used separately in such class of apparatus, the object of the invention being to provide a construction where-in the pneumatic or blower feature is used to receive the straw as it is delivered from the threshing-machine, and the endless-apron feature is utilized to deliver the straw to the stack without the great force incident to the use of a pneumatic stacker.

My invention consists in features of novelty hereinafter fully described, and pointed out in the claims.

Figure I is a perspective view of my improved stacker. Fig. II is a longitudinal sectional view of the outer end of the apron-carrier box. Fig. III is an enlarged vertical sectional view taken on line III III. Fig. IV. Fig. IV is a front elevation of the stacker.

1 designates the rear end of a threshing-machine provided with a casing 2, having a top 3, and within which a blower-housing 4 is mounted. The blower-housing 4 is provided with an eye 5 to receive the straw as it is delivered from the threshing-machine and contains a blower-fan 6. The fan 6 is carried by a shaft 7, mounted in the housing 4, and on said shaft is a beveled pinion 8, that receives the driving engagement of the beveled pinion 9 on a driving-shaft 10, equipped with a driving-pulley 11, that receives a power-belt 12. On the shaft 10 is a second pulley 13, that receives a belt 14, which leads to a pulley 15 on a shaft 16, mounted in bearings supported by the casing 2 (see Fig. IV) and having fixed thereto a beveled pinion 17.

18 designates a vertical blower-tube mounted upon the top 3 of the blower-housing casing and having communication with the interior of the blower-housing 4. This tube 18

is provided with an annular base-flange 19, that is secured upon the top of said casing. 20 is a double gear-ring having teeth upon both its upper and lower faces and loosely mounted upon said annular flange 19 to turn freely thereon. The lower teeth of the double gear-ring are arranged in mesh with the beveled pinion 17 on the shaft 16 to provide for the driving of said ring by said pinion. 60

21 designates a swinging box having vertical side walls 22 and a rear curved wall 23. The box 21 is provided with a tubular neck 24, that is fitted to the vertical blower-tube 18 to rotate thereon. 65

25 designates a straw-receiving box that is pivotally connected to the swinging box 21 by a shaft 26, bearing a roller 27, positioned within the side walls of said straw-receiving box. The straw-receiving box 25 is adapted 70 to be raised and lowered by swinging upon its pivotal shaft to position the outer end of said box at a desired elevation, so that the straw will be delivered out of the box to the stack.

28 designates elevating-cords that connect 75 the straw-receiving box to a windlass 29, mounted in arms 30, projecting from the swinging box 21.

31 is an endless apron mounted in the straw-receiving box 25 and arranged to travel on 80 the roller 27 at the inner end of said box and a roller 32 at the outer end of said box. The endless apron 31 is driven by a belt 33, mounted on a pulley 34, that is carried by the shaft 26 and receives power from a pulley 35 on a 85 shaft 36, that is geared to the upper face of the double gear-ring 20 by a beveled pinion 37.

38 designates a series of retarding-fingers mounted on a cross-rod 39, rockingly mounted in the side walls of the straw-receiving box 90 25, the fingers 38 being adapted to rest by gravity upon the straw as it passes through the box, and thereby retard its delivery by the endless apron whenever it reaches said fingers in abnormal stream, so that it will be delivered to the stack in a uniform stream. 95

In the practical use of the stacker the blower-fan 6 and the endless apron 31, that serve in unison to convey the straw from the threshing-machine to the stack, are caused 100 to operate in uniformity with each other by the combined driving mechanism that is op-

erated from the single drive-pulley 11. The blower-tube 18, which surmounts the blower-housing 4 and through which the straw passes from said housing to the straw-receiving box 25, is of less area than the interior area of the straw-receiving box, as is clearly seen in Fig. III, and by reason of this fact the force of the straw entering said receiving-box is diminished as it passes thereinto, so that it 10 will fall laterally onto the endless apron 31 instead of being blown through the box, and it is then conveyed solely and uniformly by said apron to the outer end of the box 25 to fall onto the stack with easy delivery. By 15 this construction it will be seen that provision is made for the removal of straw from the threshing-machine by a blower as rapidly as it is presented to the stacker and in a manner to prevent choking of the stacker at the 20 entrance thereof and in which the straw is subsequently delivered without the objectionable force incident to that class of stackers termed "pneumatic" and by which the straw is delivered forcibly with the expenditure of 25 a blast that ejects it from the stacker in such manner as to render it a difficult matter to control the delivery and properly build the stack.

I claim as my invention—

30 1. In a straw-stacker, the combination of a blower, a straw-receiving box into which the straw is delivered by said blower, a mechanically-operated carrier adapted to convey the straw through said box, and means for retarding the flow of straw through said receiving-box to cause it to be delivered from said box by said mechanically-operated carrier, substantially as described.

40 2. In a straw-stacker, the combination of a blower, a straw-receiving box into which the straw is delivered by said blower, an endless carrier adapted to convey the straw through said box, and means for retarding the flow of straw through said receiving-box to cause it to be delivered from said box to said endless carrier, substantially as described.

45 3. In a straw-stacker, the combination of a blower having an outlet, a straw-receiving box having an interior area greater than the outlet from said blower, a mechanically-operated carrier adapted to convey the straw through said box, and means for retarding the flow of straw through said receiving-box to cause it to be delivered from said box by said mechanically-operated carrier, substantially as described.

55 4. In a straw-stacker, the combination of a blower, an outlet-tube surmounting said

blower, a straw-receiving box swingingly mounted on said tube, a mechanically-operated carrier adapted to convey the straw through said box, and means for retarding the flow of straw through said receiving-box to cause it to be delivered from said box by said mechanically-operated carrier, substantially as described.

5. In a straw-stacker, the combination of a blower, an outlet-tube surmounting said blower, a swinging box mounted on said tube, a straw-receiving box pivotally supported by said swinging box, a mechanically-operated carrier adapted to convey the straw through said receiving-box, and means for retarding the flow of straw through said receiving-box to cause it to be delivered from said box by said mechanically-operated carrier, substantially as described.

6. In a straw-stacker, the combination of a blower, a mechanically-operated straw-conveyer adapted to receive the straw from said blower, gear mechanism having connection in common to said blower and said mechanically-operated carrier to operate them in unison with each other, and means for retarding the flow of straw through said receiving-box to cause it to be delivered from said box by said mechanically-operated carrier, substantially as described.

7. In a straw-stacker, the combination of a blower, an outlet-tube having communication with said blower, a swinging box fitted to said outlet-tube, a straw-receiving box carried by said swinging box, a traveling carrier arranged to operate in said straw-receiving box, a gear-ring mounted on said outlet-tube, gearing whereby said blower and said gear-ring are operated, and gearing providing connection between said gear-ring and said traveling carrier, substantially as described.

8. In a straw-stacker, the combination of a blower, an outlet-tube having communication with said blower, a swinging box fitted to said outlet-tube, a straw-receiving box carried by said swinging box, a traveling carrier arranged to operate in said straw-receiving box, a double-faced gear-ring mounted on said outlet-tube, gearing whereby said blower and said gear-ring are operated, and gearing providing connection between said gear-ring and said traveling carrier, substantially as described.

JOHN HEINEKE.

In presence of—

JAMES E. CALDWELL,
THOS. F. LENNOX, Jr.
